UNITED STATES PATENT OFFICE.

MATTHEW WIARD, OF PHILADELPHIA, PENNSYLVANIA.

DESIGN FOR STALL-GUARDS.

SPECIFICATION forming part of Design No. 11,721, dated April 6, 1880.

Application filed February 25, 1880. Term of patent 3½ years.

To all whom it may concern:

Be it known that I, MATTHEW WIARD, of the city and county of Philadelphia, and State of Pennsylvania, have invented an Improvement in Design for Stall-Guards, of which the following is a specification.

My invention relates to that class of stable-castings known as "stall-guards," and which are designed to prevent horses biting each other; and it consists in constructing a stall-guard of such a design that the shape commonly given to castings for this purpose is entirely dispensed with, and one of more beauty, symmetry, and strength substituted.

15 The curves of the ordinary guards are changed to straight lines, and the ornamental work forming the body of the guard is such that it corresponds to the outline of the casting, and is so shaped in cross-section that it imparts great strength to the entire guard.

Figure 1 is a side elevation of my improved design for stall-guards. Fig. 2 is a cross-section of same through line X X. Fig. 3 is a section of the rib of ornamentation. Fig. 4 is a 25 elevation of a corner.

A B C D E F G H S T represent what might be and will be called the "frame" of the guard, and really forms two parts to same, respectively I and J. The parts I and J are entirely 30 filled with a diamond-shaped ornamentation, which is composed of a thin casting, K, perforated at equal distance with diamond-shaped openings M M, and which is strengthened by oblique ribs L L and a rib, N, which entirely 35 incloses the ribbed diamond-shaped ornamentation.

The edges of the diamond-shaped ornamentation may be slightly beveled, so as to withdraw it from the sand in casting. This is 40 shown in Fig. 3. Between this rib N and the frame A B C D E F G H S T is a narrow plate, K', of casting of equal width. These ribs L L and N and the frame insure great lateral strength to the plate K K', and hence 45 the guard as a whole. This ribbed diamond-shaped ornamentation on stable-castings is used by me exclusively, so far as I am aware. Upon the sides A and B are lugs O O,

through which screws are put to secure the guard to the stall-planking. The angle 50 formed by the sides F and G is filled in by the parts P, which are composed of a rib, p, and plate p'; but this is not necessary. The angle given to the sides D, F, and G is dependent on the shape of the diamond openings 55 M M, or vice versa.

An important part of my design is that there is no segment or portion of a diamond, but halves and whole diamonds, which insure great strength to the casting, while in the common 60 shape of guards the curves given to them cut up the ornamentation into all conceivable forms and sizes, thereby giving unevenness in the distribution of metal and a corresponding loss in strength. 65

Between the sides G and H is a small part, R, bounded by sides S and T.

I do not consider that my design would be altered by dispensing with the small part R, by continuing the side G until it meets side 70 H, or even by taking away the small part J, since my design is included in making a guard of a frame composed of straight lines, as shown in the drawings, and an ornamentation of ribbed diamond-shaped orifices M M in plate 75 K K' and ribs L L N; yet I prefer to use parts J and R in constructing my stall-guard.

I do not consider it would alter the design by adding a small scroll-shaped ornamentation on any part of the bounding sides, as 80 shown in Fig. 4.

There is no expensive finishing, as drilling, on my guard.

I claim—

In design, a stall-guard constructed of 85 straight bounding sides and ribbed diamond-shaped ornamentation within said sides, substantially as described, and for the purpose specified.

In testimony of which invention I hereunto 90 set my hand.

MATTHEW WIARD.
